Inventor,

Frederick Haitz:
C. A. Snow & Co.

UNITED STATES PATENT OFFICE.

FREDRICK HAITZ, OF TOWANDA, ILLINOIS.

UMBRELLA.

SPECIFICATION forming part of Letters Patent No. 360,294, dated March 29, 1887.

Application filed June 28, 1886. Serial No. 206,471. (No model.)

To all whom it may concern:

Be it known that I, FREDRICK HAITZ, a citizen of the United States, residing at Towanda, in the county of McLean and State of Illinois, have invented a new and useful Improvement in Umbrellas, of which the following is a specification.

My invention relates to an improvement in umbrellas, adapted to be attached to a wagon or other vehicle or to an agricultural machine—such as a mowing-machine, a grain-binder, or corn-planter; and it consists in the peculiar construction and combination of devices that will be more fully set forth hereinafter, and particularly pointed out in the claims.

This invention is an improvement on the umbrella for which Letters Patent of the United States No. 326,213 were granted to me September 15, 1885.

20 In the drawings, Figure 1 is a side elevation of my invention. Fig. 2 is a vertical sectional view of the same. Fig. 3 is an inverted plan view.

A represents an umbrella-rod, which is 25 adapted to fit on the horizontal arm of an umbrella-support, such as described in Letters Patent of the United States No. 314,290, granted to me March 24, 1885, and No. 326,214, granted to me September 15, 1885, and in my 30 application for Letters Patent of the United States of even date herewith. The rod A is provided near its lower end with a detent-spring, B, and at a suitable distance from its upper end the said rod is also provided with 35 a similar detent-spring, C.

D represents a hollow cylindrical thimble, which is of considerable length and is secured to the umbrella-rod, and is free to slide vertically thereon, so as to permit the 40 said rod to be withdrawn from the thimble when it is desired to detach the umbrella from its rod. On the upper end of the rod is secured a ferrule or cap by means of a transverse pin, E, which extends through the 45 said ferrule and the upper end of the rod. This ferrule prevents the thimble D from slipping from the rod, but is removable by first withdrawing the pin E, thereby permitting the thimble D to be removed from the rod when 50 desired. The lower portion of the thimble D

is reduced in diameter, as shown, and on the said reduced portion is fitted a thimble, F, which is adapted to slide over the rod. Near the upper end of the thimble D is a circular projecting flange, D', to which the upper ends 55 of the ribs of the umbrella are pivoted in the usual manner. The thimble F is also provided near its upper end with a projecting circular flange, E', to which the lower ends of the usual stays are pivoted, the upper ends of the said 60 stays being pivoted to the ribs of the umbrella at a suitable distance from the lower ends of the said ribs.

The object of my invention is to provide an umbrella of sufficient strength to withstand 65 ordinary wind-storms and prevent the umbrella from being blown inside out and broken or destroyed by the force of the winds, and to this end I provide a third sliding thimble, I, which fits on the lower end of the thimble F. 70

From one side of the thimble I projects a pin, G, and to the thimble D is attached a depending engaging-spring, H, the lower end of which is provided with a series of openings, h, either of which is adapted to engage the pin 75 G of the thimble I, so as to secure the thimbles D, F, and I together.

To the thimble I (the upper end of which is provided with the usual grooved flange, I'), are pivoted the lower ends of a number of auxiliary stays, K. To each of the said stays, at about the center thereof, is pivoted a pair of stay-arms, K'. The outer ends of the said stays K and stay-arms K' are provided with 80 hooks k.

L represents a series of keepers, which are pivoted to the ribs of the umbrella, near the outer ends thereof. The said keepers are composed each of a strip of sheet metal bent around the rib, and having its ends pressed together 90 and provided with a transverse opening, l. The hooks k of the auxiliary stays K and the stay-arms K' engage with the openings l of the keepers, thereby attaching the said auxiliary stays and stay-arms to the ribs of the umbrella, 95 near the outer ends thereof, and thus so effectively strengthening the umbrella as to enable it to be carried in ordinary wind-storms without the danger of its being turned inside out or broken or destroyed.

In ordinary weather the auxiliary stays and stay-arms may be detached from the ribs and the thimble I detached from the thimble F, thus reducing the weight of the umbrella.

5 Having thus described my invention, I claim—

1. The combination, in an umbrella, of the thimble D, the ribs pivoted thereto, the thimble F on the thimble D and removable therefrom, the stay-rods connecting the thimble F with the ribs, the thimble I on the thimble F and removable therefrom, and the stay-rods connecting the said thimble I with the ribs, substantially as described.
- 10 2. The combination, with an umbrella hav-

ing the keepers L attached to the ribs, of the thimble I, the auxiliary stay-rods K, pivoted to the said thimble, and the stay-arms K', pivoted to the said auxiliary stay-rods, the said auxiliary stay-rods and stay-arms having the 20 hooks k, adapted to engage the keepers L, for the purposes set forth, substantially as described.

In testimony that I claim the foregoing as my own I have hereto affixed my signature in presence of two witnesses.

FREDRICK HAITZ.
